NONFLOATABLE SHANK AND MEANS FOR
SECURING SAME IN A SHOE

Samuel Zide, Brooklyn, N. Y.

Application June 13, 1932. Serial No. 617,020

1 Claim. (Cl. 36—76)

My invention relates to new and useful improvements in shoes and more particularly to shank stiffeners therefor and the method of applying same to the shoes, the primary object being to provide a new and improved shank stiffener applied in a manner which would prevent the stiffener from moving about in place between the inner and outer soles and thereby prevent the sole from becoming broken.

10 A further object of the invention resides in the provision of a shank stiffener which may be made of metal and utilized with means whereby it may be caused to adhere firmly and permanently to the inner and outer soles of the shoes to which it is applied.

20 Still another object of my invention resides in the provision of a metal shank stiffener which has a tape adhesively secured thereto and spirally wrapped therearound which may be adhesively secured permanently in place between the inner and outer soles of the shoe so as to prevent movement of said stiffener after once being introduced in place, and is known as a non-floatable shank.

25 A further object resides in providing a device which is simple and durable in construction, extremely inexpensive to manufacture and one which will be very efficient in use.

With these and other objects in view, my invention consists in the novel features of construction, combination and arrangement of parts 30 as will be hereinafter referred to and more particularly pointed out in the specification and claim.

35 In the accompanying drawing forming a part of this application:

Figure 1 is a perspective view of a shoe being formed on a last showing my improved shank stiffener applied in position;

40 Figure 2 is a transverse section therethrough as seen on the line 2—2 of Figure 1, with the last removed;

Figure 3 is an edge elevation of the shank stiffener of the usual type;

Figure 4 is a plan view thereof;

45 Figure 5 is a plan view of a shank stiffener wrapped spirally with the tape ready to be applied to use;

Figure 6 is a transverse section therethrough, as seen on the line 6—6 of Figure 5; and

50 Figure 7 is a transverse section as seen on the line 7—7 of Figure 5.

It is customary in the manufacture of ladies' shoes to introduce between the inner and outer soles thereof what is known as a shank stiffener, usually a metal strip compoundly curved with

means at one or both ends for the tacking thereof in place. In many instances, the tacking of the strip or shank stiffener is omitted because the tack would project through the very thin soles which are used in ladies' shoes. At best, only one end of the stiffener is tacked, this being the end nearest the heel. Under such circumstances the shank stiffener has a tendency to float or wobble, that is, move about in its place between the inner and outer soles. This is induced by the bending of the shoe at the shank during the natural walking process. Air pockets are formed by the movement back and forth of the soles of the shoe as the wearer walks thereon and the floating of this shank stiffener is thus further aggravated so that there is a tendency to force the outer sole away from the inner sole, causing a breaking of the outer sole at the shank portion thereof. This is particularly true with shoes wherein high heels are used and for the past few years high heels of the "spike" type have been prevailing, so that this type of shoe has been caused to break and give the wearer, the dealer and the manufacturer considerable trouble.

My improved invention contemplates the provision of a shank stiffener and means for the application thereof to use whereby the difficulties heretofore mentioned will be overcome.

In describing the invention, I shall refer to the drawing in which similar reference characters 85 designate corresponding parts throughout the several views and in which the numeral 1 designates a last about which is being formed a shoe, the upper of which is designated by the numeral 2. This upper is secured in the usual manner 90 to the inner sole 3 and applied thereto in the usual manner is the outer sole 4.

95 A shank stiffener designated by the numeral 5 is provided, the same being of a type known to the art and clearly shown in Figures 3 and 4 of the drawing. This particular type of stiffener is formed of metal, compoundly curved and wider at one end than at the other, the wide end being adapted to be applied adjacent the heel portion of the shoe. The intermediate portion of this 100 shank stiffener is grooved as shown at 6 and at the wider end there are provided the openings 7 while at the smaller end of the stiffener there is provided a single opening 8. These openings permit the stiffener to be tacked in place if desired, although, as stated above, it is frequently the case that tacks are not used or merely one tack used at the end adjacent the heel.

105 Being formed of metal, it would be difficult to get an adhesive which would enable the stiffener 110

to adhere to leather. In order to provide a means whereby an adhesive may be used to secure the stiffener against floating, I wrap the stiffener 5 with a tape 9, said tape having an adhesive on its inner face to readily adhere to the stiffener 5 and said tape is spirally wrapped thereon, as shown in Figure 5 with slight spaces between the convolutions. Being grooved as shown at 6, pockets are thus formed in the stiffener. This 10 stiffener is then applied in place on the inner sole and the outer sole applied thereto but in applying the stiffener in place, a heavy adhesive as designated by the numeral 10 is applied to both faces of the wrapped portion of the shank 15 stiffener. This adhesive enters the pocket formed by the groove 6, enters between the convolutions of the wrapped tape and fully saturates said tape. Preferably a single tack is applied through one of the openings 7 to secure the base portion of the 20 stiffener in place and the adhesive fully applied to both sides of the wrapped stiffener will securely bind said stiffener in place between the inner and outer soles and prevent said stiffener from floating or moving out of place. The natural 25 bending of the shoe during walking will not cause the stiffener to become displaced and thus the many difficulties encountered heretofore, due to the floating or moving of the shank stiffener, will be obviated.

30 The application of the spirally wound tape on the metal stiffener permits the adhesive to become effective when applied thereto. The ap-

plication of this tape and the adhesive is a simple and inexpensive step in the process of shoe manufacture so that the cost of the shoe is not increased but the durability of the shoe is greatly increased.

80 From the foregoing description of the construction of my improved shank stiffener and the method of applying the same to use, the value and effectiveness thereof will be readily understood and it will be seen that I have provided a simple, inexpensive and efficient means for carrying out the objects of the invention.

85 While I have particularly described the elements best adapted to perform the functions set forth, it is obvious that various changes in form, proportion and in the minor details of construction may be resorted to without departing from the spirit or sacrificing any of the principles of the invention set forth in the appended claim.

90 Having thus described the invention what is claimed is:

95 In a shoe including an inner sole, an outer sole, a metal shank stiffener interposed therebetween and provided with a longitudinal groove, and an adhesive tape wrapped spirally around said stiffener providing pockets in the grooved portion of said stiffener and an adhesive applied to the inner and outer faces of said wrapped stiffener and in the pockets thereof to firmly secure said stiffener in position between said soles. 100
